UNITED STATES PATENT OFFICE

111,652

DESIGN FOR A HAIR CURLER

Edgar Beresford Gilleland, Los Angeles, Calif.,
assignor of one-half to George W. Gilleland,
Kansas City, Mo.

Application July 25, 1938, Serial No. 78,711

Term of patent 3½ years

To all whom it may concern:

Be it known that I, Edgar Beresford Gilleland, a citizen of the United States, residing in the city of Los Angeles, in the county of Los Angeles and State of California, have invented a new, original, and ornamental Design for a Hair Curler, of which the following is a specification, reference being had to the accompanying drawing, forming a part thereof.

I claim:

The ornamental design for a hair curler, substantially as shown.

EDGAR BERESFORD GILLELAND.
